CLAIM

The ornamental design for a solar powered figurine, as shown and described.

DESCRIPTION

FIG. 1 is a front elevational view of the solar powered figurine showing my design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front perspective view thereof; and,

FIG. 8 is front perspective view of a second embodiment thereof, showing the design in an alternate position.
